UNITED STATES PATENT OFFICE

130,578

DESIGN FOR A DOOR AND WINDOW GRILLE

Benjamin H. Carmeen, Memphis, Tenn., assignor to National Guard Products, Inc., Memphis,
Tenn., a corporation of Tennessee

Application May 5, 1941, Serial No. 100,769

Term of patent 7 years

To all whom it may concern:

Be it known that I, Benjamin H. Carmeen, a citizen of the United States of America, residing at Memphis, in the county of Shelby and State of Tennessee, have invented a new, original, and ornamental Design for Door and Window Grilles, of which the following is a specification, reference being had to the accompanying drawing, forming part thereof.

Fig. 1 is a front elevational view of a door or window grille showing my new design.

Fig. 2 is a sectional view taken along the line II—II of Fig. 1.

I claim:

The ornamental design for a door and window grille, substantially as shown.

BENJAMIN H. CARMEEN.
